PHILLIP KRAKAUER, OF BROOKLYN, NEW YORK, ASSIGNOR TO KAY MANUFACTURING CO., OF BROOKLYN, NEW YORK, A CORPORATION OF NEW YORK.

SPRING-CUSHION STRUCTURE.

Application filed March 7, 1924. Serial No. 697,444.

This invention relates to spring cushions and particularly to the structure of that type of cushions in which each spring is held in an individual pocket.

5 The various objects of my invention can best be understood from the description which follows, and from the accompanying drawings, in which,

Fig. 1 is a combined top plan view and a 10 partial horizontal section of a cushion structure embodying my invention, and

Fig. 2 is a vertical section of the same taken on the line 2—2 of Fig. 1.

Fig. 3 is a perspective view of one of the 15 continuous partitions as it appears when seamed into position, and Fig. 4 is a front view of one of said partitions before it has been bent and seamed into position.

A cushion structure economical in the use 20 of materials and labor, and adapted for the rapid insertion of the springs thereinto has long been sought and has heretofore been only approximated.

Spring cushions have heretofore been 25 made largely in units, each unit comprising a complete row of springs entirely encased and ready for insertion into a casing, each spring being contained in an individual, substantially cylindrical pocket. It has been 30 found that the structure just described is wasteful of material due to the duplication of material for covering the ends of the pockets. Other cushions have, therefore, been made with substantially square pock- 35 ets for individual springs by seaming partitions to the top and bottom of a casing and thereby utilizing the casing for one or both of the ends of the pockets.

My improved structure contemplates the 40 use of a partly open semi-cylindrical and semi-square pocket, whereby I am enabled to save considerable material and am further able to use a minimum of labor in the assembly thereof.

45 An outer casing as 10 preferably all of one piece of material, has secured thereto suitable continuous strips as 11 substantially of the same width as the height of the completed pockets, together with the seamed 50 edges 21 and 22 thereof, as will be more fully described hereinafter. Said casing is preferably folded substantially midway, after the attachment to the top 14 and to the bottom 15 thereof, of one of the edges as 55 21, and 22 respectively of each strip 11, so

that the peripheral edges of said casing may later be brought together and seamed as at 13 to form a closed structure, complete with springs as 12 suitably held therein. To stretch the casing 10 into its preferably rectangular prismatic form, wherein a top 14, a bottom 15, sides 16 and 17, and edges 18, are formed, reliance is preferably had upon the extension of the springs 12 into contact with said top 14 and bottom 15 after said 60 springs have been inserted into the unseamed casing, as will be more fully described hereinafter.

I prefer to arrange each partition forming strip 11 so that its general direction proceeding from one end to the other is substantially parallel to one of the sides of the cushion structure. It will be noted that said partition strip 11 extends from one of the sides of the cushion as 16 to the opposite 70 side as 17, and is made of a single continuous strip of material so shaped as to form three of the walls, 19, 20 and 31 of the interior 75 spring holding pockets 32. To form said walls, I prefer to bend said strip into sinuous form in such a manner that each of the resulting walls is substantially perpendicular to the adjacent walls of the strip, or in other words, the alternate walls are substantially parallel to each other and to the same 80 side of the cushion structure.

Said walls, 19, 20 and 31 cooperate with a corresponding wall of the adjacent partition to form the complete pocket. Before assembling the pocket structure, I prefer to 85 mark on the inner surface of the top 14 and of the bottom 15 of the casing 10, lines substantially in the form of a series of squares indicating in which positions and at which points the partitions 11 are to be seamed. 90

Each of said partitions 11 are slotted inwardly from the edges 21 and 22 a sufficient distance to allow said strip to be bent readily into the perpendicular pocket walls 19, 20 and 31, as by means of the slits 40, each 100 substantially perpendicular to the edges of said partition. By reason of said slits, I am enabled to round the corners of the pocket at the juncture of the walls 19, 20 and 31 to follow substantially the cylindrical shape 105 of the spring 12, as will be seen from Fig. 3. This results in a considerable saving of material since it is well known that the surface of a cylinder is of considerably less area than that of a square prism, the sides of 110

the base of which are of the same length as the diameter of the cylinder. Furthermore, by reason of the divergence of the edges of the slits 40, when a convex surface as 41 between the walls 19 and 33 is formed, I eliminate the creases and folds which would otherwise result when the partition 11 is bent at right angles to form said walls, thereby making the seaming of the edges 21 and 22 to the casing 10 as by means of the seams 23 and 24, a rapid and simple operation, requiring little time and effort. Similarly, when the concave surface as 42 between the walls 20 and 31 is formed, the end of one of the edges 22 of one wall naturally adjusts itself into a position in which it overlaps the edge 22 of the adjacent wall with the same advantages respecting ease of seaming, elimination of creases and saving of material. A further advantage arising from the use of the slits 40 is that said slits act as guides to the operator when seaming the partitions in place, so that he may stop sewing when the edge of the slit is reached, thereby preventing accidents and waste of time and material in running the seam too far in one direction.

It will be seen that by shaping the strip 11 to form three of the walls of each of the pockets 32, a series of corresponding walls 33 of alternate pockets of a row and adjacent to the walls 31 and 19, are formed in alignment with each other, a second series of walls 20 parallel and in spaced relation to said walls 33 are similarly formed, a third series of walls 19 connect one end of each of the walls 33 to an end of the wall 20, and a fourth series of walls 31 connect the other end of each of the walls 20 to the other end of each of the walls 33.

For the outer rows of pockets 34, only three walls are needed, the remaining wall of the pocket being preferably formed by the sides 17 or 18 of the casing 10. For economy of material, the pockets 35 in the row immediately adjacent to the edge 18 of the casing may be formed of a U-shaped strip as 36, though, if desired, a long, continuous strip 11 may obviously also be used in said row.

It will be noted that the strips 11 are entirely independent of, and are unconnected to each other in any way, whereby a series of openings as 25 of substantial size is formed between adjacent strips, through which openings a suitable spring carrying tool, or the hand carrying a compressed spring may be passed through the cushion structure to reach any one or all of the pockets in a row. It will be obvious from said spaces that considerable material is eliminated, without loss of the spring enclosing effect of the pocket, since said pocket being stitched at the top and bottom, and said spaces being made preferably substan-

tially less than the diameter of the spring 12, prevent undue displacement thereof.

It will be understood that for the purpose of inserting the springs 12 into their respective pockets, one of the sides as 17 is preferably left unseamed until after the insertion of said springs.

To insert the springs 12 into the pockets therefor after the casing 10, and the partitions 11 have been substantially completely seamed together, the hand containing a compressed spring may be inserted between the partitions, through the spaces 25.

I prefer, however, to fill the alternate pockets of each of two adjacent rows in staggered relation by means of a suitable tool adapted for that purpose. In other words, I prefer to fill alternate pockets in one row at the same time that alternate pockets in the adjacent row, diagonally of the pockets in the first mentioned row are being filled, so that certain pockets to the left of a given row of spaces 25 are being filled simultaneously with the filling of certain other pockets to the right of said row of spaces.

After insertion of the springs into the pockets has been completed, the unseamed edges of the casing 10 are brought together, and readily seamed by the stitching 13, completing the structure, and maintaining the parts in their permanent operative relation.

Only one thickness of material is provided at all parts of each pocket of my improved cushion for purposes of economy, while aligned spaces 25 are provided, for allowing the rapid insertion into the pockets of an entire series of springs at a time, if desired. It will be seen that my improved arrangement of the pocket forming partitions 11 provides an individual pocket of peculiar shape for each spring, is economical of material, due particularly to the slits 40, and may be rapidly seamed to the casing with little expenditure of labor.

I do not wish to limit myself to the specific structure shown, as various changes may be made therefrom, as in the manner of folding the edges 21 and 22, in the length and position of the slits 40, and in the insertion of the springs into their pockets, and in the size of the spaces 25, without departing from the spirit of my invention.

I claim:

1. In a spring cushion structure, a series of continuous pocket forming partitions extending from one of the sides to the opposite side of the said structure, and walls, bent from said partitions for forming three of the sides of the interior pockets of said structure, the fourth wall of each of said interior pockets being formed by one of the walls of the similarly bent adjacent partition said fourth wall being spaced from the first mentioned walls for providing spaces at two of the adjacent corners of each of said pockets.

2. In a spring cushion structure, means forming a series of pockets substantially square in cross section with partly cylindrical interiorly concave rounded portions at the 5 points corresponding to two of the adjacent corners of the square and openings at the points corresponding to the remaining corners of the square, comprising a series of sinuous partitions arranged across said 10 structure and between the sides thereof, a pair of substantially parallel walls substantially parallel to said sides and a wall substantially perpendicular to and joining said parallel walls bent from said partitions, one 15 of said perpendicular walls of the adjacent partition serving as the fourth wall of each of said pockets, and a casing seamed to the upper and lower edges of said partitions and forming the top and bottom of said pockets, 20 and a spring in each of said pockets.

3. A spring cushion construction of the class described, comprising a top, a bottom spaced therefrom and a plurality of partition walls ranging across the top and bottom 25 and connected to the latter on serpentine lines, whereby to provide a plurality of rows of pockets, the alternate pockets of each row having their open sides directed reversely to the open sides of the intermediate pockets 30 and arranged with respect to the contiguous

pockets so that the closed sides of the pockets of one row are disposed opposite to the open sides of the pockets of the neighboring rows.

4. A spring cushion construction of the class described, comprising a top, a bottom spaced therefrom, and a plurality of partition walls ranging across the top and bottom, each of said walls providing a plurality of pockets open at one side only, the alternate 35 pockets of each row having their open sides directed reversely to the open sides of the intermediate pockets, one of the closed sides of each pocket of a row being disposed opposite to and closing the open side of a pocket 40 of a neighboring row.

5. A spring cushion construction of the class described, comprising a top, a bottom spaced therefrom, and a plurality of partition walls ranging across the top and bottom, 45 each of said walls being continuous and providing a plurality of rectangular pockets each of which is open at one side only, the alternating pockets of each row having their open sides directed reversely to the open 50 sides of the intermediate pockets, one of the closed sides of each pocket of a row being disposed opposite to and closing the open side of a pocket of a neighboring row.

PHILLIP KRAKAUER.
